UNITED STATES PATENT OFFICE.

JOHN GRAVES, OF NEW YORK, N. Y., ASSIGNOR, BY MESNE ASSIGNMENTS,
TO FRANK T. MORRILL, OF SAME PLACE.

SHEET-METAL MANTEL.

SPECIFICATION forming part of Letters Patent No. 625,104, dated May 16, 1899.

Application filed August 27, 1897. Serial No. 649,764. (No model.)

To all whom it may concern:

Be it known that I, JOHN GRAVES, a citizen of the United States, residing in New York, (Brooklyn,) in the county of Kings and State 5 of New York, have invented certain new and useful Improvements in Sheet-Metal Mantels, of which the following is a specification.

The improvements in mantels forming the subject of this invention consist in so constructing mantels made of sheet metal as to greatly increase the adaptability and facilitate the application of this class of mantels and to lessen their cost of manufacture.

The main feature of this invention consists 15 in making the wall-plates separate and independent of the main portion of the mantel, which, with the exception of the shelf, comprises all the parts, as the frieze, pilasters, profiles, &c., preferably made of a single piece 20 of a suitable sheet metal. This permits of the use and application of mantels of a given size to chimneys of different widths, as the detached wall-plates of given widths may be set up so as to extend more or less, as the case 25 may be, within the profiles of the mantel, the edges of said profiles resting and bearing against the fronts of the wall-plates. This is a very advantageous feature of construction, for with mantels in which the wall-plates are 30 integral with the other parts it is very difficult and sometimes impossible to adapt a given size or design of mantel to the chimney it may be selected for.

The invention also embodies an improved 35 brace and fastening device adapted to stiffen the mantel and to provide a means by which it may be secured in place against the chimney.

To describe my invention more particularly, I will now refer to the accompanying drawings, forming part of this specification, in which—

Figure 1 is a front elevation of a mantel embodying my improvements. Fig. 2 is a horizontal section taken on the line 2 2, Fig. 1. 45 Fig. 3 is a perspective view of the brace and fastening-piece; and Fig. 4 is a vertical section taken on the line 4 4, Fig. 1.

Mantels of this description are formed or stamped up in suitably-constructed dies from 50 sheet metal, sheet-steel being generally and preferably used for the purpose. The man-

tel proper, here shown so formed, comprises a frieze A, pilasters B B, and profiles CC, the inner edges of said profiles being turned inwardly to produce the flanges D D, which add 55 strength and rigidity to these parts of the mantel and perform the functions hereinafter described. The inner edges of the pilasters or the facings of the pilasters are turned inwardly to form the flanges E E, and the lower 60 edge of the frieze is also turned inwardly to form the horizontal flange F. These flanges E E and F constitute the boundary of the grate-opening and add strength and rigidity to the parts of the mantel from which they 65 extend. To further strengthen and stiffen the main portion of the mantel, I make use of bracing-pieces G, formed of strips of metal, as shown in perspective, Fig. 3, in such shape as to extend from the inner edges of 70 the profiles CC along or adjacent to the wall of the chimney and outwardly to the inturned edges of the pilasters B B. The ends H of the pieces G are riveted to the flanges D D, and the ends I are riveted to the flanges E E, two 75 of such pieces being attached to each side of the mantel, as shown by the dotted lines in Fig. 1, one near the lower ends, as shown in Fig. 2, and one at the top of the pilasters, as shown in Fig. 4. These pieces G are preferably 80 corrugated to add to their rigidity and are employed to secure the mantel to the wall by means of the hooks J J, which are driven into the wall before the mantel is set up, and when the mantel is in place their hooked ends 85 are bent or twisted, so as to embrace the central parts of the pieces G, extending along the wall, which parts are curved outwardly to impart resilience thereto, so that when engaged by the hooks the mantel is held firmly in position. Two only of these bracing and fastening pieces G are shown at each side of the mantel. It will be understood that more may be used if thought desirable.

The wall-plates K K are separate from and 95 independent of the mantel proper. They are made of sheet metal channeled or with the edges turned up, which edges are placed against the wall and pressed somewhat into the plaster, so as to insure the said wall-plates 100 being held securely in position.

In setting up a mantel of this description

the wall-plates K K are placed in their right positions and relatively to the corners of a projecting chimney when the mantel is to be applied to such, as shown, L L, Fig. 2, representing the profiles of a chimney, the flanged edges of the wall-plates being pressed into the plaster facing of the wall. The sheet-metal mantel is then placed in position with the flanges D D of the profiles bearing against the faces of the wall-plates. The hooks J J, previously driven into the wall in the right positions, are then bent or twisted so their hooked ends catch over the central parts of the brace fastening-pieces G G, which are pressed or sprung toward the wall and which by their resilience hold the mantel firmly against the wall-plates and the wall. The wall-plates used in combination with the other parts of the mantel, applied as here shown, are, as will be seen, considerably wider than is necessary in the particular application of the mantel, a considerable part of them being behind the mantel, and it is evident that they may be set out much farther when a mantel of the size shown is to be applied to a wider chimney. The spaces between the inner edges of the pilasters B B and the wall are then filled with bricks M M, thus forming the chimney-jambs or a continuation of the chimney-jambs when the mantel is applied to an open fireplace. The upper part of the opening is also bricked up, the outer ends of the lower layer of bricks N resting on the internal flange F of the frieze. The other parts of the space behind the pilasters may be filled with any suitable material or rubble, as may also be the upper part of the frieze, instead of its being entirely filled with bricks, as shown.

The shelf O is represented as composed of sheet metal. It may be made of slate or other suitable material and secured in position by any suitable means in such manner as is well understood.

The junctures of the brace and fastening pieces G G and the flanges D and E, as well as the adjacent faces of the flanges D D and wall-plates K K, are for perspicuity shown

separated in the drawings. It will of course be understood that these parts will be in close intimate contact, the rivets drawing the parts 50 they connect firmly together and the heads of the rivets on the outside being countersunk.

The central part of the mantel is shown open. Summer-boards, registers, and analogous devices may be applied thereto in the 55 usual manner.

I claim as my invention—

1. In a mantel, the combination of a main piece comprising a frieze, pilasters and profiles formed of a single piece of sheet metal 60 with the edges of the pilasters and of the profiles turned in to form flanges, bracing and stiffening pieces of strip metal extending between the flanges of the pilasters and profiles with their ends connected respectively to said 65 flanges, the parts of said bracing-pieces extending along the wall being curved to impart resilience thereto, and hooks driven into the wall and embracing the curved parts of said braces. 70

2. In a mantel, the combination of main piece comprising a frieze, pilasters and profiles formed of a single piece of sheet metal with the edges of the pilasters and of the profiles turned in to form flanges, bracing and 75 stiffening pieces of strip metal extending between the flanges of the pilasters and profiles with their ends connected respectively to said flanges, the parts of said bracing-pieces extending along the wall being curved to impart 80 resilience thereto, hooks driven into the wall and embracing the curved parts of said braces, and wall-plates of separate pieces of sheet metal with their edges turned up so as to extend into the wall and held in adjusted position behind the pilasters by the edges of the profiles. 85

In testimony whereof I have hereunto subscribed my name.

JOHN GRAVES.
